UNITED STATES PATENT OFFICE.

HORACE L. MARKLAND, OF WACO, TEXAS.

ARRANGEMENT AND EQUIPMENT FOR SHOE-SHINING SHOPS.

Application filed February 3, 1922. Serial No. 533,950.

To all whom it may concern:

Be it known that I, HORACE L. MARKLAND, a citizen of the United States, residing at Waco, in the county of McLennan and State 5 of Texas, have invented certain new and useful Improvements in Arrangements and Equipments for Shoe-Shining Shops, of which the following is a specification.

This invention relates to shoe shining and 10 polishing means and it pertains more particularly to an arrangement, construction and association of parts comprising a shoe shining shop.

The invention aims to provide a shoe 15 shining shop having an interior arrangement of furniture and shoe shining equipment with particular reference to its pleasing, harmonious and artistic appearance, having due respect to its operation along 20 practical lines.

A particular object of the invention is the arrangement wherein patrons may pay as they enter, no "tips" being permitted, and suitable and convenient seating arrangement being provided for accommodation 25 of customers waiting their turn when the shoe shining seats are all occupied. There is also provided a separate row of shoe shining seats with a divisional wall of 30 frosted glass between so that ladies and gentlemen may have separate service. There is also provided in the rear of the shop a ladies' dressing or rest room, a store room for stock, and toilet rooms. The invention 35 aims to provide in general a clean, respectable and inviting shoe shining shop where undue noise and the loud verbal invitations to enter, as generally prevail in shoe shining parlors or stands, are eliminated.

40 The invention will be more fully understood by reference to the following description, taken in connection with the accompanying drawings, forming part hereof, in which—

45 Figure 1 is a plan view of a shoe shining shop embodying my invention.

Figure 2 is an interior sectional view looking toward the front end of the shop, the view being taken on line 2—2 of Figure 1.

50 Figure 3 is a view similar to the view in Figure 2, but looking toward the rear of the shop and taken on line 3—3 of Figure 1.

Figures 4 and 5 are longitudinal sectional views of the interior of the shop, the views

being taken along lines 4—4 and 5—5, respectively, and looking toward the direction of the arrows; and

Figure 6 is a detail sectional view of one of the shoe shining seats with foot rests.

Referring more particularly to the drawings, 1—1 denote the side walls and 2—2 the rear and front walls of a building wherein the equipment and furniture of the shoe shining shop are arranged, 3 denoting the street entrance. A turnstile, electrically 65 operated (means not shown) is shown at 4, on the opposite sides of which are a cashier's room, window or office 5, and a waiting room 6. The waiting room 6 is provided with seats 7 and a table 8 for books, newspapers and reading matter for patrons waiting for service at the shining stand.

The shoe shining stand comprises a number of seats 9—9 with foot rests 10—10 arranged on one side of the wall as depicted 75 in Figure 1, and a divisional wall 11 is provided to form a separate compartment for each sex, the largest or front compartment with the greatest number of seats being intended for gentlemen and the rear 80 compartment for ladies. 12 is a passageway between the two compartments and 13 is a seat for the ladies' operators, preferably colored girls.

At the rear of the shop and along the 85 back wall 2 are a ladies' rest room, or dressing room 14, a store room 15, and toilet rooms 15^a, all provided with doors as shown. At suitable intervals on the walls are panels 16 for advertising matter, the panels 16 in 90 Figure 5 being in a conspicuous position, i. e., in front of the customers on the seats 9—9 and just above the wainscoting 17. A panel 18 is located above the doors 15 also 95 for advertising purposes.

It is understood, of course, that there are various types of shoe shining parlors, the interior of which are somewhat similar to this invention, but it should also be understood that the present arrangement is a 100 departure therefrom in the particular style and arrangement of equipment and furniture, also the entrance feature.

What is claimed is—

A shoe shining and polishing shop having 105 in combination a main entrance from the street, a cashier's ticket window and a waiting room, a reception room between the

cashier's window, waiting room and front wall of the shop, a passageway between the cashier's window and the waiting room for entrance of customers to the interior of the shop, a turnstile in said passageway located in convenient reach of the ticket window; said interior of the shop provided with shoe

shining seats in separate compartments for ladies and gentlemen, and a ladies' rest room, a store room, and toilet rooms in the rear of the shop.

In testimony whereof I have signed my name to this specification.

HORACE L. MARKLAND.
